UNITED STATES PATENT OFFICE.

CHARLES W. EBEL, OF LA FAYETTE, INDIANA.

TRAY.

Application filed May 16, 1925. Serial No. 30,726.

To all whom it may concern:

Be it known that I, CHARLES W. EBEL, a citizen of the United States, residing at La Fayette, in the county of Tippecanoe and 5 the State of Indiana, have invented a certain new and useful Improvement in Trays, of which the following is a full, clear, concise, and exact description.

My invention relates to trays, the tray of 10 my invention being formed in relatively adjustable sections whereby one section may be superimposed upon the other for purposes of shipment and storage. In accordance with one characteristic of the invention one 15 tray section is provided with legs that are adapted to stably support this section, the other tray section having a leg or legs adapted only partially to support it, the first tray section cooperating with the legs of the 20 second tray section to stably support the latter tray section. A railing is desirably provided upon each tray section and where each tray section is provided with a railing the railings of both tray sections are together 25 around the entire tray when the tray is adjusted for use. In order that the space occupied by the tray, when folded, may be reduced as much as possible the railings on the tray sections are in nesting relation 30 when the tray sections are folded together.

The tray of my invention is of a special utility when constructed to have one section capable of supporting an infant's bath tub, the other tray section serving to hold the 35 infant in preparation for or after its bath. The tray, when employed for this purpose, is desirably constructed of woven wire and the legs that support the tray sections are desirably formed and arranged to rest upon 40 the rim of an adult sized bath tub. Any water which may spill from the infant's bath tub or otherwise fall toward the bottom of the tray will find a passage to the larger bath tub beneath.

45 The invention will be more fully explained in connection with the accompanying drawings in which Fig. 1 is a side view illustrating an adult sized bath tub, partially in section, a tray of my invention supported upon 50 the rim of this bath tub and an infant's bath tub supported upon one of the sections of the tray; Fig. 2 is a plan view of the parts illustrated in Fig. 1, omitting the infant's bath tub; Fig. 3 shows the tray with 55 its sections folded together; Fig. 4 is a sectional view of the part of the structure on

line 4—4 of Fig. 2; Fig. 5 is a sectional view on line 5—5 of Fig. 4 and Fig. 6 is a perspective view illustrating portions of the two tray sections at one of the hinges that 60 join the sections. The tray sections 1 and 2 are desirably formed of woven wire. The tray section 1 has a wire railing extending partially around it and composed of a heavy upper rail 3 and bracing connections of wire 65 4 which join the rail 3 with the heavy wire rim 5 of said section 1. The other tray section is similarly formed with a heavy wire rim 6 and is provided with a railing that extends completely around it. This has a heavy wire rail portion 7 which is joined with the heavy wire rim 6 by bracings 8 of wire. Hinge pintles 9 are carried by the heavy wire rim 6 of the tray section 2, these 70 pintles being the out turned ends of heavy 75 wire bracket like portions 10 which are assembled with the wire rim 6 by the hooks 11 which are wrapped about the wire portions 6 and 10. These pintles 9 are thus carried by the sides of the tray section 2. Hinge 80 sockets 12 are formed in the downward continuations 3' of the wire rail portion 3 that are located substantially in line with the sides of the tray section 2 and the structure is made very firm by means of soldered 85 joints 13 between the downward continuations 3' of the wire rail portion 3 and the heavy wire rim 5 of the rail section 1. The hinge sockets, which receive the pintles are 90 substantially midway between the rail portion 3 and the bottom of the tray section 1 having this rail portion. The gap between the downward continuations 3' of the heavy wire railing portion 3 is sufficient to permit the tray section 2 to be swung into the space 95 surrounded by the railing upon tray section 1 when the tray is folded, the railings upon the two trays nesting one within the other, when tray is folded, to economize space for 100 shipment and storage. When the tray is opened for use the inner transverse edge of the railing upon tray section 2 closes the gap that is in the adjacent portion of the railing of the other tray section 1. The arrangement is thus such that the railings upon both tray sections are around the entire tray when the tray is opened for use and one of these railings is disposed entirely around the tray section carrying it and 105 serves to close the gap in the railing upon the other tray section.

The tray of my invention finds a very

useful embodiment when constructed and arranged to support the infant's bath tub, illustrated at 14. This bath tub is desirably supported upon the smaller tray section 2 leaving the larger tray section to hold the infant in preparation for or after its bath and also to hold various toilet articles to be used in connection with the bath. It is desirable to support the tray at a height which 10 will not make the bathing of the infant laborious, and to this end the tray is desirably constructed so that it may be supported upon an adult sized bath tub 15. The tray 1 is desirably provided with a number of 15 legs 16 having feet 17 conforming to the rim 18 of the bath tub 15, these legs serving stably to support the tray section 1 upon the bath tub 15. In order that the legs 16 may be adapted to rest upon bath tubs of 20 different sizes I desirably form these legs with upper horizontal branches 19 which are adjustably assembled with anchors 20 formed of strip iron located at and assembled with the bottom of the tray section 1. The 25 anchors 20 are formed with slots 22 and the leg branches 19 are formed with slots 23 registering with slots 22 or lapping the same according to the adjustment effected. The anchors 20 carry depending bolts 24 passing 30 through the slots 23 and having heads which underlie the legs branches 19. Bolts 25 pass freely through the slots 22 and 23. These bolts have heads 26 which overlie the anchor plates 20. They also have wing nuts 27 which underlie the leg branches 19. When the legs are to be adjusted inwardly or outwardly the wing nuts 27 are loosened and when the desired adjustment has been secured they are tightened. The tray section 40 2 is shown with two legs 28 near its outer, curved, end, these legs being constructed similarly to the legs provided for the tray section 1, but desirably being further connected with the tray section 2 by 45 wire struts 29. The two legs 28 provided for the tray section 2 cooperate with tray section 1 and the legs that stably support this tray section in stably supporting tray section 2.

50 It is obvious that the tray of my invention may be adapted to be supported upon other supports than the rims of bath tubs. It is also obvious that the tray of my invention is adapted for other uses than the use 55 herein particularly set forth.

Changes may be made without departing from my invention.

Having thus described my invention, I claim:

60 1. A tray formed in sections that are hinged together, one of these tray sections having a railing terminating at the sides and hinged edge of the second tray section which latter tray section has a railing

around it, the transverse portion of this latter railing at the hinged edges of the tray sections substantially closing the gap between the ends of the first railing when the tray is adjusted for use, the second tray section being receivable within the railing of 70 the first when the tray sections are superimposed, one upon the other.

2. A tray formed in sections that are hinged together, one of these tray sections having a railing terminating at the sides 75 and hinged edge of the second tray section which latter tray section has a railing around it, the transverse portion of this latter railing at the hinged edges of the tray sections substantially closing the gap between the ends of the first railing when the tray is adjusted for use.

3. A tray formed in sections that are hinged together and having railings that are together around the tray when the tray is adjusted for use, the railing upon one tray section being continued across this section at its hinged edge to be individually around this section.

4. A tray formed in sections that are relatively adjustable to permit one to be superimposed upon the other, one of these tray sections having a railing terminating at the sides and adjacent transverse edge of the second tray section which latter tray section has a railing around it, the transverse portion of this latter railing at the adjacent transverse edges of the tray section substantially closing the gap between the ends of the first railing when the tray is adjusted for use, the second tray section being receivable within the railing of the first when the tray sections are superimposed, one upon the other.

5. A tray formed in sections that are relatively adjustable to permit one to be superimposed upon the other, one of these tray sections having a railing terminating at the sides and adjacent transverse edge of the second tray section which latter tray section has a railing around it, the transverse portion of this latter railing at the adjacent transverse edges of the tray sections substantially closing the gap between the ends of the first railing when the tray is adjusted for use.

6. A tray formed in sections that are relatively adjusted to permit one to be superimposed upon the other and having railings that are together around the tray when the tray is adjusted for use, the railing upon one tray section being continued across this section at the adjacent transverse edges of the tray sections to be individually around this section.

In witness whereof, I hereunto subscribe my name.

CHARLES W. EBEL.
